[57] CLAIM

The ornamental design for a water-proof, vented housing for an emergency light unit, as shown and described.

DESCRIPTION

FIG. 1 is a front elevational view of a water-proof, vented housing for an emergency light unit, showing the preferred embodiment of the new design;

FIG. 2 is a right side elevational view of the water-proof, vented housing for an emergency light unit of FIG. 1, the left side being a mirror image thereof;

FIG. 3 is a rear elevational of the water-proof, vented housing for an emergency light unit of FIG. 1;

FIG. 4 is a top plan view of the water-proof, vented housing for an emergency light unit of FIG. 1; and,

FIG. 5 is a bottom plan view of the water-proof, vented housing for an emergency light unit of FIG. 1.

The emergency light is shown in broken lines only and forms no part of the claimed design.
